UNITED STATES PATENT OFFICE

144,006

DESIGN FOR AN AIRPLANE

John W. Thorp, Burbank, Calif., assignor to
Lockheed Aircraft Corporation, Burbank,
Calif.

Application April 23, 1945, Serial No. 119,152

Term of patent 14 years

(Cl. D71—1)

To all whom it may concern:

Be it known that I, John W. Thorp, a citizen
of the United States, residing at Burbank, in the
county of Los Angeles and State of California,
have invented a new, original, and ornamental
Design for an Airplane, of which the following
is a specification, reference being had to the
accompanying drawings, forming a part thereof.

Figure 1 of the drawings is a top plan view of
an airplane embodying the new design,

Figure 2 is a front elevational view thereof;

Figure 3 is a side elevational view thereof;
Figure 4 is a perspective view taken from a
point below, slightly ahead of, and to one side
of the airplane while in flight.

I claim:

The ornamental design for an airplane, sub-
stantially as shown.

JOHN W. THORP.
